BENJAMIN ANDREWS, OF HOUSTON, TEXAS.

METHOD AND APPARATUS FOR RAISING LIQUIDS.

Application filed July 25, 1923. Serial No. 653,746.

My invention relates to that type of apparatus employing air or a non-condensable gas to raise water, oil or other liquids from wells or other sources having comparatively great depths. It is similar to apparatus heretofore known a "air lifts" which are made operative by co-mingling with the liquid to be raised, air or gas introduced at or near the bottom of a pipe or conduit, 10 deeply submerged in the liquid, so that through the influence of the gas or air introduced, the mixture in the conduit is made sufficiently light to be caused to flow upward because of the greater pressure exerted at 15 the intake due to its submergence in the liquid to be raised.

While the above described principle of the air lift is basic, I have discovered that successful and economical operation is governed by two distinct actions, namely: by 20 displacement, principally in cases of short lifts, with comparatively large submergence; and by impact, principally in cases of long lifts with comparatively little submergence. 25 It is with this latter action that my invention chiefly has to do. Mass and velocity being functions of impact of the fluid medium involved, this invention contemplates their regulation not only by governing the quantity and pressure of the active medium, as is the general practice, but also by governing the intake of fluid being raised. Apparently the latter has not heretofore 30 been done.

Air lifts have usually been used where the intake of the riser can be located at a considerable depth below the natural head of oil or water to be pumped. When this head or submergence is not available, it is necessary to provide an artificial head. This 40 artificial head may be produced in a number of ways, one of which I have illustrated and described in this application. The principal feature of this invention, whether the appliance is operated under a natural or an artificial head or submergence, is the control of the inflow of the liquid into the education conduit or riser so that the back pressure of the mixture of liquid and gas shall be maintained at the most efficient point for the best 45 action of the air lift. For practicability of construction and convenience of operation I have here adopted the jet siphon principle for securing artificially the effect of the

required submergence, because the air or 55 gas producing the jet at the same time supplies the necessary gaseous medium for lightening the liquid column. In other words, my invention relates to an accurate adjustment or control of the average specific 60 gravity of the air and liquid in the pipe as it flows upward, so that the static or gravitational back pressure thereof is never sufficient to counterbalance the upwards pressure due to the velocity head maintained by the 65 air jet. For a detail description of one form of my invention, which I describe for the purpose of illustrating the principle thereof, reference may be had to the following specification and to the accompanying 70 drawing forming a part thereof in which

Fig. 1 is a sectional view of a well, such as a water or oil well, the apparatus at the head of the shaft being shown in elevation; 75 and

Fig. 2 is a sectional view of the lower end of one form of my improved apparatus whereby the control of the flow is automatically carried out.

Referring to the drawing, the numeral 1 80 indicates the casing or lining of an oil or other well, such as is usually provided for driven wells. The numeral 2 indicates a central pipe through which the liquid is raised by means of the air jet 3 supplied 85 with compressed air through the pipe 4. The upper end of the pipe 2, which, for convenience, will be referred to as the riser, is provided at its upper end with a suitable pipe fitting 5, to which the horizontal delivery pipe 6 is pivoted in any suitable manner, as indicated at 7. The top of the fitting 5 is provided with a cap 8, which carries a lifting screw 9 which passes through the cross head or yoke 10 of the supporting frames 90 11. The screw 9 engages a hand wheel having an axial screw threaded opening forming a nut which supports the screw and the entire structure attached to it. The hub of the hand wheel is preferable provided with an anti-frictional thrust bearing where it rests on the yoke 10, as indicated at 13. The pipe 4 is held in position at its upper end in any suitable way, such as by passing through a lug 14 carried by the fitting 5 and is provided 100 with a fitting or connection 15 which allows the air supply pipe 16 to turn in a vertical plane relative to pipe 4. The air supply 105

pipe 16 is also preferably provided with a controlling valve 17.

- The parts above referred to need not be in the form or arrangement described, as any similar construction for accomplishing the same results may be used instead. The lower end of the riser 2 is preferably slightly reduced in size, as indicated at 20, so that the end of the jet 3 is located at or near the most restricted point. The lower end of the pipe 2 is provided with a flanged foot piece or member 21 having a tapering opening therein, as illustrated at 22. The flanged portion of the member 21 carries a downwardly projecting spider 23 which holds in position a ring or guiding member 24. Through this member passes the movable valve member 25 having a conical or tapering end, as clearly illustrated in the drawing. The valve member 25 is provided at its lower end with an extended base which may take any suitable form, but is shown in the form of four arms 26 at right angles to each other. A compression spring 27 surrounds the valve member 25 and rests against a bearing ring 28 which is held in position by the sleeving 24. The arms 26 are provided with upwardly extending rods 29 which pass through the flanged member 21 and are provided with heads to prevent disengagement. The operation of the apparatus, as just described, may be explained as follows: The riser 2 with the air supply pipe 4 with all of the parts attached to the lower end thereof, is lowered into the well in any suitable or well known manner until the foot member 26 rests upon or is near the bottom of the well. The supporting structure with the pipes 6 and 16 is then placed in position. The hand wheel 12 is then turned until the foot piece 26 rests on the bottom of the well and the opening 22 is partially closed by the movable valve member 25. The valve 17 is then opened and air admitted to the nozzle 3. After sufficient time the jet 3 will force mixed air and oil or other liquid through the riser 2, from which it will be ejected at the top through the pipe 6, the amount of flow and its velocity depending upon the relative proportions of the air and liquid. The hand wheel 12 then may be turned either to raise or lower the riser 2 and its attached pipe 4, so that the opening 22 is adjusted to permit an inflow of oil or other liquid so that the same, after passing the jet 3, will have the correct average specific gravity to obtain the maximum volume of flow at the top of the well.
- The maximum flow is obtained not only when the liquid issues from the well in a fine mist or spray, but when the atomization has taken place at the intake of the eduction tube, and when a continuous stream of finely comminuted liquid in suspension in the gaseous medium has been maintained through-

out its transit of the eduction tube. The atomization of the liquid is obtained by the impact of the gaseous medium against the liquid drawn upwardly past the valve 19 and around the nozzle 3 of the gaseous inlet. The rate of inflow of liquid past the valve must be regulated in amount so that, when the liquid is acted upon by the blast of the gaseous medium through the constricted channel 20, it will be thoroughly broken up into a fine spray which will be maintained in its atomized condition and carried upwardly in the stream of gaseous medium to the surface.

It is, of course, very desirable that the intake valve at the bottom of the riser be controlled automatically. In Fig. 2 I have illustrated an arrangement which I have designed for this purpose. The numeral 2 indicates the riser similar to that illustrated in Fig. 1. To the lower end of this riser is attached a corrugated, preferably a metallic, tube 30, which carries at its lower end a tapering intake portion 31. Where the parts 30, 31 are joined together, a suitable collar 32 is provided, which forms a bearing for the compression spring, indicated at 39, the purpose of which will be described later. Adjacent the lower end of the tapering member 31 is the nozzle 33 connected with the bend 34 which is supplied with air through the pipe 4' similar to the pipe 4 in Fig. 1. The upper end of the nozzle 33 projects into the tapering intake member 31 and its lower portion forms a valve member with said intake member, the space between said parts being varied as hereinafter described. A cylindrical casing 35, through which the bend 34 passes, surrounds the corrugated pipe 30 and the tapering portion 31. This casing carries internal collar 36 adjustably secured in position in any suitable manner, such as by the screws 37. Upon collar 36 rests a flanged bearing plate 38 which holds in position the lower end of a compression spring 39. The annular ring 32 rests upon the top of the spring 39 and guides the corrugated tube 30 above referred to. Adjacent the lower end of the riser 2 is a screw threaded bushing 41 which is fixed in position thereon in any suitable manner. The screw threads of bushing 41 engage internal screw threads 42 at the upper end of the casing 35, which also is provided with a laterally extending bracket 43, serving as a support for the air pipe 4'.

The operation of this form of my device is as follows: Assuming that air is being forced through the pipe 4' under pressure, and issued from the nozzle 33 into the restricted portion 31 of the riser. This draws the oil from the lower part of the casing into said restricted portion and forces the mixed oil and air upward in a certain portion, depending upon the space between

the nozzle 33 and the end of the restricted portion 31. This will produce a definite pressure within the corrugated elastic portion 30 of the riser, depending upon the head or the height to which the liquid is to be raised. If the pressure in said riser becomes so great that the upward flow tends to be stopped or retarded, the pressure within the corrugated elastic portion 30 will be increased, thereby producing a downward pressure upon the restricted portion 31, which pressure depends upon the difference in cross section between the smallest diameter of said restricted portion and the diameter at its upper end, as will be readily understood by one familiar with hydrostatics. This pressure will compress spring 39, thereby forcing the restricted portion 31 to a lower position, which reduces the amount of space between the nozzle 33 and the lower end of the restricted tube 31. Thus the flow of oil will be reduced and the percentage thereof mixed with the air is thereby lessened, so that the specific gravity of the mixture in the riser 2 is also reduced, thereby decreasing the static head. This will allow the upward flow of the liquid to again resume its normal velocity until the same is again changed by some external condition. It will be appreciated from the above that the reverse action takes place should pressure within the riser 2 be reduced below the normal amount, so that the space between the nozzle 33 and the tube 31 is increased, allowing more liquid to enter the latter. The tension of said spring 39 may be adjusted before the riser is in a well by placing the screws 37 in the proper position and by rotating the pipe so that the screw threads 41 raise or lower the casing and consequently the collar 36, thereby relieving or partly releasing the compression of the spring 39.

From the above description it will be seen that I have provided a simple and efficient means for controlling the intake of liquid at the lower end of the riser of an air jet, and upon this means depends the successful operation of air jets of this type for raising liquids, particularly when comparatively large static heads are to be overcome, such as in the case of deep oil wells.

I do not wish to be understood as being limited to the details of form and arrangement of parts set forth, for various changes may be made by those skilled in the art without departing from the spirit and scope of my invention, nor do I wish to be understood as being limited to the use of the apparatus described in the raising of petroleum or crude oil from oil wells, for the device is capable of various applications which will be obvious from the general principles involved in its operation.

Neither do I wish to be understood as being

limited to the use of air under pressure as a means for causing the flow of the liquid, for any suitable gas, such as natural gas, may be used in place thereof.

What I claim and desire to protect by Letters Patent is:

1. The method of raising liquids which comprises, supplying at a point adjacent the base of a column of the liquid to be raised, a non-condensable gaseous medium under substantially constant pressure and causing a variable quantity of said liquid to be mixed with said gaseous medium at said point so that said liquid will be mixed with said medium in such amounts as to maintain a pressure of said liquid and gaseous medium such that a substantially constant upward flow of said mixture is produced and variation in external hydrostatic head is counteracted.

2. The method of raising liquids which comprises, supplying at a point adjacent the base of a column of the liquid to be raised, a non-condensable gaseous medium under substantially constant pressure and controlling the inflow of the liquid at the base of said column so as to maintain a back pressure of the liquid laden gaseous mixture lower than that of the variable head of the liquid being raised.

3. The method of raising liquids which comprises, supplying at a point adjacent the base of a column of the liquid to be raised, a non-condensable gaseous medium under substantially constant pressure and controlling the inflow of the liquid at the base of said column so as to maintain a back pressure of the liquid laden gaseous medium lower than the effective pressure of the gaseous medium.

4. The method of raising liquids which comprises, supplying at a point adjacent the base of a column of the liquid to be raised, a non-condensable gaseous medium under pressure and controlling the pressure of the liquid laden air at the base of said column by regulating the rate of inflow of the liquid being raised in accordance with the variable back pressure of said mixture.

5. The method of raising liquids which comprises, supplying at a point adjacent the base of a column of the liquid to be raised, a non-condensable gaseous medium under pressure, and controlling the pressure of the liquid laden gaseous mixture at the base of said column at a point lower than the operative head of the gaseous medium by regulating the rate of inflow of said liquid to be raised in an inverse proportion to the pressure of said mixture.

6. The method of raising liquids which comprises, supplying at a point adjacent the base of a column of the liquid to be raised, a non-condensable gaseous medium under pressure, controlling the pressure of

- the liquid laden gaseous medium at the base of said column so that said pressure shall be lower than the operative head of the gaseous medium by regulating the rate of inflow of 5 said liquid being raised in an inverse proportion to the pressure of said mixture. 70
7. The method of raising liquids which comprises, supplying at a point adjacent the base of a column of the liquid to be raised 10 a non-condensable gaseous medium under substantially constant pressure, the base of said column of liquid being submerged in the body of the liquid, and regulating the admission of the liquid to said column to 15 such an amount that the effective back pressure of the mixture of said gaseous medium and said liquid is maintained at a point lower than that produced by said gaseous medium and said submergence. 80
- 20 8. The method of raising liquids which comprises, supplying at a point adjacent the base of a column of the liquid to be raised a non-condensable gaseous medium under substantially constant pressure, and controlling 25 the admission of liquid at the base of said column according to the variable external head thereof so that the difference between the effective back pressure of the mixture of the gaseous medium and liquid 30 is maintained at such an amount that the pressure of said gaseous medium will produce a substantially constant upward flow of said mixture. 90
9. The method of raising liquids which 35 comprises, supplying at a point adjacent the base of a column of the liquid to be raised an upwardly directed flow of a suitable non-condensable gaseous medium under substantially constant pressure whereby the liquid 40 in said column is aerated and its gravitational pressure reduced to a point substantially lower than that of the liquid drawn in by said flow, and regulating the inflow of said liquid whereby a back pressure of the mixture 45 is produced that is substantially less than the pressure of said gaseous medium. 100
10. A device for raising liquids, comprising an eduction pipe adapted to extend into the liquid to be raised, a nozzle within 50 said pipe for producing an upward flow of a suitable non-condensable gaseous medium under pressure, a valve in said eduction pipe, and controlling means connected with said eduction pipe and adapted to operate 55 said valve to restrict the flow of the liquid to be mixed with said medium, so that the effective back pressure of the mixture is made substantially less than the pressure of said medium. 110
- 60 11. A device for raising liquids comprising, a pipe adapted to extend into the liquid to be raised, means for producing an upward flow within said pipe of a suitable non-condensable gaseous medium under 65 pressure, an automatic liquid inlet-valve for controlling the intake of said liquid, and operating means therefor actuated by the back pressure above or beyond said flow producing means so that said back pressure is substantially less than that of said gaseous medium. 70
12. A device for raising liquids comprising, a pipe adapted to extend into the liquid to be raised, a nozzle within said pipe for producing an upward flow of a suitable non-condensable gaseous medium under pressure, an automatic liquid inlet valve controlling the flow of liquid past said nozzle and operating means therefor actuated by the back pressure above or beyond said nozzle 80 so that said back pressure is substantially less than that of said gaseous medium. 75
13. A device for raising liquids comprising, a pipe adapted to extend into the liquid to be raised, means for producing an upward flow in said pipe of a suitable non-condensable gaseous medium under pressure, said pipe having an inlet opening adjacent its lower end, a valve member for varying the area of said opening to control the intake of said liquid and means for varying the relative positions of said valve member and said opening and operated by the back pressure above said flow producing means. 85
14. A device for raising liquids comprising, a pipe adapted to extend into the liquid to be raised, means for producing an upward flow of a suitable gaseous medium under pressure, said pipe having an inlet opening adjacent its lower end, a valve member for varying the area of said opening to control the intake of said liquid, means for automatically controlling the relative positions of said opening and said valve member and means for actuating the same by the variations of pressure above said flow producing means and below said opening. 95
15. A device for raising liquids comprising, a pipe adapted to extend into the liquid to be raised, means in said pipe for producing an upward flow of a suitable gaseous medium under pressure, said pipe having an opening adjacent its lower end, a valve member for varying the area of said opening to control the intake of said liquid 100 and means for automatically controlling the relative positions of said opening and said valve member comprising, a chamber having longitudinally extensible elastic walls and provided with a fluid pressure receiving part upon which the pressure within said pipe is adapted to act, resilient counterbalancing means adapted to oppose said pressure and determine the relative normal positions of said opening and said valve member and controlled by the variations of pressure above said opening. 110
